UNITED STATES PATENT OFFICE

ENOCH RECTOR, OF NEW YORK, N. Y., ASSIGNOR TO RECTOR GASIFIER COMPANY, OF WAUKESHA, WISCONSIN, A CORPORATION OF WISCONSIN

OIL-GAS GENERATOR

Application filed November 22, 1926. Serial No. 149,876.

This invention relates to oil gas generators, and more particularly to oil gas generators of that class in which heavy liquid fuel is subjected to heat treatment.

In generators of various types now in common use, difficulty is frequently encountered due to condensation. Condensation is due largely to the fact that the fuel is delivered to the engine cylinder in the form of a vapor mixed with air at atmospheric temperature resulting in condensation of the fuel on the cylinder walls and the formation of minute globules, causing very appreciable loss due to the fact that the fuel globules will not readily ignite and explode. This also renders it impossible to obtain a fuel mixture of uniform consistency and causes deposition of carbon in the cylinder. Detonation, or premature explosion of the fuel mixture, is probably due largely to excessively high temperature of the fuel in vaporous form. Various attempts have been made to overcome condensation by heating the fuel to a high temperature before it enters the engine cylinder in vaporous form. These attempts have not met with any great success, as heating the fuel to a high temperature increases rather than diminishes detonation, as long as the fuel is supplied to the cylinder in vaporous form. I have found that this is true, by repeated experiments, even when the fuel is heated to a much higher temperature than that required in the ordinary operation of the engine and is delivered to the cylinder in the form of a vapor. In fact, my experiments indicate that it is impossible, from a practical standpoint at any rate, to prevent condensation when using heavy fuel, so long as the fuel is delivered to the cylinder in the form of a vapor, even though the fuel in this form may be heated to a high temperature. It is possible, however, to produce a thoroughly satisfactory fuel which is free from condensation and detonation by altering the physical and chemical properties of the liquid hydrocarbon ordinarily used in connection with internal combustion engines so as to produce fixed gases from such hydrocarbons.

As above noted, it has been attempted here-

tofore to avoid condensation of heavy liquid fuel by heating the fuel to a high temperature and delivering it to the engine cylinder in the form of a vapor. Various forms of apparatus have been devised for thus heating and vaporizing the fuel. In certain of these devices the fuel is passed over and about heated coils or similar elements so as to be vaporized thereby and heated to a comparatively high temperature, after which this vaporized and heated fuel is drawn into the engine cylinder. In other forms with which I am familiar, it has been proposed to heat and vaporize the fuel by means of a flame to which the fuel is subjected, a portion of the fuel being employed for supporting combustion. In all of these devices, however, it has been considered essential to prevent combustion of the fuel which is delivered to the engine cylinder, and great care has been taken to keep the temperature of this fuel sufficiently low to prevent combustion and to insure that the fuel will be vaporized only and heated to a comparatively high temperature, this hot vaporized fuel being then mixed with air and delivered to the engine cylinder. It is to be noted that the fuel treated in this manner is delivered to the engine cylinder in the form of a vapor heated to a comparatively high temperature, but the chemical and physical characteristics of the fuel are not altered, as it remains a hydrocarbon and is merely in the form of a vapor. The vaporizing and heating of heavy gaseous fuel in this manner has proved to be unsatisfactory and does not eliminate or materially reduce condensation. I have found that it is possible to carry this general method referred to a step further and by so doing produce a gaseous fuel which is thoroughly satisfactory and which very effectually eliminates detonation and condensation. The nature of this fuel permits of a higher compression than vaporized hydrocarbon fuel, thus giving a greater expansion ratio. In practicing my invention, I do that which the methods and apparatuses above referred to have been very careful to avoid, i. e., I subject the liquid hydrocarbon fuel to incomplete combustion instead of merely heating and vaporizing such fuel. This results

in changing the physical and chemical characteristics of the fuel producing, instead of a highly heated vapor, fixed gases which are readily combustible and, when mixed with air, are highly explosive. These gases are mixed with atmospheric air so as to reduce their temperature and produce an explosive mixture, this mixture being then drawn into the engine cylinder and exploded in a known manner.

It is therefore one of the main objects of my invention to provide an oil gas generator and means associated therewith of simple and efficient construction whereby hydrocarbon fuel in liquid form may be readily subjected to incomplete combustion so as to be converted into fixed gases, means being provided for cooling these gases and mixing the same with atmospheric air for producing an explosive mixture which is drawn into the engine cylinder. A further object is to provide simple and efficient means whereby the operation described can be carried on continuously during operation of the engine. Another object is to provide simple and efficient means whereby the proper relation between the air flow and the feed of the fuel to the means for producing and maintaining incomplete combustion of the fuel will be automatically maintained. Another object is to provide means for producing a zone of continuous combustion which is complete, in conjunction with the means for producing a zone of incomplete combustion, means being provided whereby the proportion of the flow of fuel to the zone of complete combustion can be accurately adjusted in relation to the flow of fuel to the zone of incomplete combustion so as to obtain the best working conditions for a given hydrocarbon and engine in connection with which the carburetor is used. Further objects will appear from the detailed description.

In the drawings:—

Fig. 1 is a side view of an oil gas generator constructed in accordance with my invention, the hood and associated parts being omitted;

Fig. 2 is a plan view of the lower section of the generator;

Fig. 3 is a vertical central section through the generator taken substantially on line 3—3 of Fig. 2;

Fig. 4 is a fragmentary sectional view on an enlarged scale taken substantially on line 4—4 of Fig. 2;

Fig. 5 is a section taken substantially on line 5—5 of Fig. 4;

Fig. 6 is a fragmentary sectional view taken substantially on line 6—6 of Fig. 2;

Fig. 7 is a section taken substantially on line 7—7 of Fig. 2; and

Fig. 8 is a fragmentary section taken substantially on line 8—8 of Fig. 2.

The oil gas generator includes a casing 1, the top of which is of generally rectangular

shape and is closed by a plate 2 secured in position by means of cap screws 3, or in any other suitable or preferred manner. A hood 4 is secured on the upper face of plate 2 and is provided with a conduit 5 having an outer peripheral flange 6 which is secured, by means of bolts 7 and nuts 8, to pipe 9 of the intake manifold of an internal combustion engine. A throttle valve 10 is mounted in conduit 5 in a known manner and is operated by well known means. A valve seat member 11 is mounted in hood 4 beyond conduit 5, the opening of this member being normally closed by an inwardly opening air inlet valve 12 seating therein. This valve is of a known construction and is normally held seated or closed by a light coil spring 13 mounted about the stem 14 of the valve and confined between the valve and an abutment 15 carried by the hood structure. A plunger 16 is provided at the lower end of stem 14 and operates in a dash pot 17 provided in an off-set 18 of the casing 1. This air inlet valve is of a well known construction in this art and need not be illustrated and described in detail.

The casing 1 includes a main cylindrical portion or section 19 closed at its lower end by a head 20 having an outer peripheral flange 21 which is secured by bolts 22 and nuts 23 to a similar flange 24 on the cylindrical portion 19. A main complete combustion chamber 25 is mounted in portion or section 19. This main combustion chamber includes a cylindrical body 26 and a base 27 upon which the body seats, this base being provided with an inner annular flange 28 fitting snugly into the lower end of the body. The base seats upon a tubular boss 29 extending upwardly from the central portion of member 20 and is provided with a depending tubular neck 30 which extends through this boss and is secured in position by a nut 31 threaded onto the neck and bearing tightly against the outer face of boss 29. A drain cock 32 is threaded into neck 30 for draining off the contents of body 26 when required. The complete combustion chamber 25 is disposed in concentric spaced relation to the cylindrical portion 19 of the casing 1, and member 27 is spaced away from the bottom of member 20. This provides a space 33 about the main combustion chamber to which water is supplied from a water container or reservoir 34 provided with a flanged outlet member 35 secured by cap screws 36 to a block 37 extending from cylindrical member 19, this block being provided with a suitable bore 38 which registers with a similar bore 39 of outlet member 35. Water is supplied to the reservoir 34 from a suitably located main supply tank (not shown), by means of a suitable supply tube or pipe 40. The supply of water to the reservoir 34 is controlled by a float and a valve associated therewith and this control of the water supply serves to maintain the level of

the water jacket about the main combustion chamber 25 substantially permanent. The construction and arrangement of the float and valve for controlling the water level is well known in this art and need not be illustrated or described in detail, and any other suitable or preferred means for supplying water to the water jacket and maintaining the level thereof substantially constant can be employed.

The upper edge of body 26 of the main complete combustion chamber is beveled at 41 for seating the similarly beveled lower end of a flange 42a depending from a partial combustion chamber section 42. The partial or secondary combustion chamber includes a Venturi element 43, the neck opening 44 of which is of small cross area relative to the cross area of the main combustion chamber. This Venturi element is connected to flange 42a by an inwardly extending annular shoulder 45. The partial combustion chamber, proper, includes the space within member 43 and between plate 2 and the neck opening 44 of the Venturi element 43. Steam inlet tubes 46 are secured in this shoulder and extend downwardly into the upper portion of the main combustion chamber 25, these tubes being open at both ends and communicating at their upper ends with the space between a pair of baffles 47 which extend outwardly radially of the upper portion of the secondary combustion chamber and space this chamber away from the surrounding wall of the cylindrical portion 19. The tubes 46 alternate with air inlet tubes 48 secured to the shoulder 45. Each tube 48 communicates at its upper end with a bore 49 provided in a thickened portion 43a of the inclined wall of the Venturi element, this thickened portion integrally connecting the inclined portion of the venturi and the shoulder 45, the bore 49 being disposed at an inclination substantially parallel with the inclined portion of the Venturi element. The outer end of bore 49 registers with an air inlet port 50 provided in the cylindrical portion 19 of the casing. This construction will be understood more clearly from Figs. 4 and 5. As will be noted more clearly from Fig. 3, the air inlet tubes 48 extend downwardly to within a short distance of the bottom of the complete combustion chamber 25, the lower ends of the tubes 46 being spaced a considerable distance above the bottom of this chamber. While I have referred to the member 42 as the secondary combustion chamber section, for convenience, it is to be understood that the space enclosed by the member 26 and the portion or flange 42a of the section 42 constitutes the main combustion space or chamber. Plate 2 is provided with an opening 51 through which direct communication is established between the hood, and the upper portion of the sec-

ondary combustion chamber. This opening 51 is preferably disposed eccentric to the neck opening 44 of the Venturi element 43 as an additional safeguard against combustion and possible consequent explosion of the gases taking place within the hood 4, as will be later explained.

As will be understood more clearly from Fig. 5, by alternating the elements 43a of the venturi and the pairs of baffles 47, I provide openings or passages 52 by means of which steam generated in the water jacket about the main combustion chamber can flow upwardly between the sets or pairs of baffles, this steam then flowing downwardly between the baffles of each pair and through the tubes 46 into the main combustion chamber 25 above the bottom thereof. The shoulder 45 of the Venturi element 43 is provided with an additional thickened portion 43b through which extends a main oil supply duct 52' which opens at its inner end into the Venturi opening 44. The outer end of this duct registers with a port 53 extending through the wall of the cylindrical portion 19 and communicating with the lower end of a vertical duct 54 in the off-set 18. The upper end of duct 54 is connected by a short horizontal passage 55 to a vertical duct 56 which is connected at its central portion by a port 57 to a vertical duct 58 having an enlarged lower portion 59, the lower end of which is closed by a screw plug 60 to permit draining and cleaning out of the duct. Fuel is supplied to duct 59 from an oil reservoir 61 having a neck 62 which is flanged and secured by cap screws 63 to an offset 64 of the offset or dash pot structure 18. Offset 64 is provided with a bore 65 extending from the duct 59 and in register with a similar bore 66 in neck 62 of the fuel reservoir 61. Oil is supplied to reservoir 61 from a main supply tank through a suitable tube or pipe 66 and the oil level is controlled by a float operated valve, the normal oil level in the duct 59 being at substantially the center of the bore 65. As the valve and the float means for operating the same for controlling the oil level are well known in this art, it is not necessary to further describe or illustrate this part of the construction.

A valve seat member 67 of substantially double Venturi shape is mounted in the upper end of duct 59 and accommodates an upwardly tapering valve 68 at the lower end of a stem 69 threaded in a sleeve 70 which is secured in valve 12 in a known manner. This valve 68 moves with the air valve 12 so as to control the flow of oil to the duct 52 in accordance with opening and closing of the air valve. The construction and arrangement of this valve is known in this art and need not be illustrated or described in detail, it being understood that the valve operates to control the flow of oil to the

main oil supply duct in direct accordance with the flow of air into the hood 4 and through duct or conduit 5 thereof. Offset 64 is further provided with a duct 71 extending from the duct 65 and establishing communication between the same and the dash pot 17 adjacent the lower end thereof. This insures that a supplemental supply of oil is at all times in the lower portion of the dash pot. The vertical duct 56 is connected to the dash pot adjacent the lower end of this duct by a port 72 (Fig. 7). This port is controlled by a needle valve 73 slideable through a packing gland structure 74. This valve is provided adjacent the outer end of its stem with spaced collars 75 between which extends a fork 76 at the upper end of a lever 77 pivoted at 78 in the bifurcated outer end of an arm 79 extending from the dash pot structure 18. This lever is connected above the pivot 78 to the dash pot structure 18 by a tension spring 80 which acts to urge the valve 73 inwardly. Lever 77 is provided at its lower end with a fork 81 which receives the shank of an adjusting screw 82 threaded through a lug 83 extending from the bottom of the dash pot structure 18. Movement of the fork 81 away from lug 83 is limited by a disc 84 on the outer end of screw shank 82. By adjusting the screw 82 the extent to which the valve 73 is opened, is determined and the valve is normally held in this adjusted position by the spring 80. As the duct 56 is located beyond the valve 68, the valve 73 and port 72 provide means whereby oil can be supplied to the generator when the engine is running at low speed or idling, the air inlet valve 12 being normally closed, or substantially so, at such time. As the fork 81 of the lever 77 is free to move toward the lug 83, the valve 73 can be moved manually outwardly so as to open the port 72 beyond its normal extent, permitting a greater flow of oil to the generator, when this seems desirable or necessary. This arrangement of a valve to permit supply of oil from the dash pot to a carburetor when the air inlet valve is closed, that is, when the engine is idling or running at low speed, is known in this art, and I do not claim this feature of construction except in so far as it cooperates with the means hereinafter described for accomplishing the desired result. By arranging the duct and the main control valve 68 in the manner illustrated and described, oil will be supplied to the main oil duct 52 during operation of the engine, and this oil will be caused to be projected in a sheet across the opening 44 of the neck of the venturi, and the amount of oil thus supplied will vary in direct accordance with the amount of air which enters the hood 4 through the opening of valve 12. This provides means for continuously supplying oil to the zone of in-

complete combustion thus continuously producing gases which are combustible and, when mixed with air, are highly explosive.

Dash pot structure 18 is provided with a lateral extension 84 having a horizontal duct 85 which communicates at its inner end with the upper end of a vertical duct 86 extending from the oil duct 71. A valve member 87 is threaded into extension 84 from the upper face thereof, this member being provided with a central bore 88 and a reduced lower end portion 89 having a plurality of radially disposed ports 90 communicating with bore 88. The member 87 is further provided with an enlarged head 91 having radial ports 92 communicating with a threaded bore provided in this head for reception of a valve screw 93, the lower end of which is tapered to provide, in effect, a needle valve element 94 adapted for cooperation with a valve seat 95 formed at the upper end of the bore 88. A supplementary oil supply duct 96 extends from the space 97 above the lower reduced portion 89 of the valve member 87 and has its outlet end disposed between a pair of the baffles 47 above one of the steam inlet tubes 46. During operation of the engine, suction will be created in both of the combustion chambers which will result in inducing oil through the ducts 52 and 96. The amount of oil which is induced through the supplemental duct 96 will depend, to a great extent, on the amount of air which is admitted to the ports 92, so that by adjusting the valve screw 93 toward or away from its seat 94, the proportion of oil which flows through the duct 96 relative to the oil which flows through duct 52, can be accurately adjusted, and this proportion will remain substantially constant, as any increase in the partial vacuum created in the combustion chamber will affect the flow of oil through both of the ducts similarly. By arranging and relating the ducts in the manner illustrated and described, and providing the means for effecting the initial adjustment of the control valve, I insure the proper ratio between the feed of the oil to the respective combustion zones for different speeds of operation of the engine, and I also insure that the amount of gases produced will vary in direct and proper proportion to variations in the amount of air admitted to the hood 4, so as to produce an explosive mixture of high efficiency at the various operating speeds of the engine. It is also to be noted that the supply of oil to the various ducts and to the zones of combustion is continuous, the flow of oil to the combustion zones being metered by the upwardly flowing products of combustion, insuring a continuous supply of a mixture of air and gases to the engine at all times and eliminating any loss in efficiency such as would result from intermittent operation of the combustion means.

In starting the generator, a small charge of one of the lighter hydrocarbons, such as gasoline, is injected into the main combustion chamber 25 through one of the openings 50 and the associated air tube 48. This charge is then ignited by means of a spark plug 98 of standard construction secured in a nipple 99 extending from the cylindrical portion 19 of the casing 1, this spark plug extending through a lug 100 formed on the upper section or member 42 of the complete combustion chamber, this lug being suitably drilled to accommodate the spark plug which extends into the upper portion of the main or complete combustion chamber 25. This spark plug is connected in a suitable circuit and operates, in a known manner, during operation of the engine. Preferably, though not necessarily, cylindrical portion 19 of the casing is provided with a nipple 102 which registers with a lug 103 extending from section 42 of the main or complete combustion chamber structure, this lug having a bore 104 which registers with the bore of the nipple. The nipple has mounted therein a window structure 105 for permitting observation of the interior of the combustion chamber. It will be understood, however, that the window structure and associated parts may be omitted if desired.

After the initial charge has been placed in the main combustion chamber 25 and the engine has been set in operation, oil will be drawn from reservoir 61 through the ducts 52' and 96. The oil which is discharged through the duct 96 will flow downwardly through the tube 46 into the main combustion chamber 25. This oil forms a pool within the member 27, the upper face of which member is of inverted conical shape. The oil is vaporized from the surface of this pool and serves to support continuous combustion in this chamber. It is also to be noted that the oil discharged through tube 46 drips therefrom and passes through the zone of combustion so as to be heated and partially vaporized thereby, this assisting in maintaining combustion in the main combustion chamber. After the generator has been in operation but a short time, the water surrounding the main combustion chamber 25 is heated sufficiently to generate steam, and this steam enters the combustion chamber through the tubes 46, as previously described. The air for supporting combustion in the main chamber 25 enters through the tubes 48 at the lower end of this chamber, and this air is in excess of that required for supporting combustion of the fuel oil admitted through the duct 96. In addition to providing means for generating steam, the water jacket about the main combustion chamber performs the additional important function of cooling the zone of complete combustion and serves to prevent the tem-

perature of the chamber 25 from exceeding 500 degrees F. and, under normal conditions, maintains the temperature of this chamber below 500 degrees F. This feature is of importance as I have found that the heavier hydrocarbons, such as kerosene and fuel oil, which I intend to use in connection with this generator, will carbonize when brought into contact with objects heated to a greater temperature than 500 degrees F. By providing this water jacket for the main combustion chamber, therefore, I prevent carbonizing of the oil and also generate steam which enters into the combustion chamber. The heat within the combustion chamber causes the oil to react with the steam so as to convert a portion of the steam which enters such chamber into hydrogen and oxygen, the oxygen combining with carbon from the hydrocarbon, forming carbon monoxide (CO). This carbon monoxide and the liberated hydrogen become thoroughly mixed and commingled with the gases produced. This mixture contains a sufficient amount of moisture to prevent the formation of carbon in the engine cylinder, which is a very desirable feature of my invention.

Simultaneously with the creation of a zone of complete combustion in the lower chamber 25, oil is projected across the opening 44 of the venturi in a sheet from the main oil supply duct 52. This sheet of oil is instantaneously ignited from the burning oil in the chamber 25, but complete combustion of the main supply of oil does not take place due to the excess of the oil which is projected across the opening of the neck of the venturi over the air in conjunction with the cooling effect of this sheet of fuel and the expansion of the fuel oil which takes place as it flows upwardly in the venturi. It is an important feature of my invention, however, that the combustion in the upper or secondary combustion chamber, comprising the space within member 43 and between neck 44 and plate 2, while being incomplete, is of sufficient extent to alter the physical and chemical characteristics of the oil and convert the oil into fixed gases. The incomplete combustion of the main supply of oil results in the production of a relatively large amount of carbon monoxide (CO) and it is thought that under the influence of the heat and partial combustion a large proportion of the carbon dioxide (CO₂) resulting from the complete combustion in chamber 25 combines with the carbon liberated from the main fuel supply to form carbon monoxide (CO). In addition to the production of a large quantity of carbon monoxide, it is probable that there are other gases produced, such as hydrogen, marsh-gas or methane (CH₄), ethane (C₂H₆), and possibly other gases. All of these gases are fixed and, when combined with air, produce a highly explosive

mixture. By this means I render it possible to employ the heavy hydrocarbons in connection with internal combustion engines, such hydrocarbons being subjected to incomplete combustion in the manner described so as to be converted into fixed gases, which gases are then mixed with air within hood 4, this mixture being drawn into the engine cylinders. As the gases are fixed, it is possible to mix with these gases a comparatively large volume of cold atmospheric air so as to cool the gases before entry of the same into the engine cylinders, not shown. This cooling of the gases, combined with the fact that these gases are fixed and have a different molecular construction, prevents condensation and detonation and the explosive mixture produced is of much higher efficiency and of much more uniform consistency than any mixture which it is possible to produce by merely vaporizing the hydrocarbon fuel and mixing this vapor with air. It is also to be noted that in my generator the process of converting the hydrocarbon fuel into fixed gases is continuous once it has been initiated, and the amount of fuel required to support the complete combustion in the chamber 25 is very small and the saving effected in fuel consumed is sufficiently great to much more than offset this small amount of fuel used in the main combustion chamber, so that the oil gas generator is much more economical than carburetors of ordinary construction which are in common use, in addition to the fact that the oil gas produced is highly efficient and eliminates condensation and detonation which it is impossible to eliminate when employing a fuel mixture in vaporous form, such as is employed in carburetors of ordinary construction.

What I claim is:—

1. In an oil gas generator, means for generating combustible gases comprising, a main complete combustion chamber, a partial combustion chamber above and aligned with the main chamber and including a Venturi element having direct communication through its neck with the main chamber, means for supplying oil and air to the main chamber in proper proportions for maintaining complete combustion therein, means for projecting oil across the neck of the Venturi element from the periphery thereof and in a sheet extending across the neck radially thereof, and a take-off hood communicating with the upper end of the partial combustion chamber through a restricted opening.

2. In an oil gas generator, means for generating combustible gases comprising, a main complete combustion chamber, a partial combustion chamber above the main chamber and including a Venturi element having direct communication through its neck with the main chamber, means for supplying oil

and air to the main chamber in proper proportions for maintaining complete combustion therein, means for projecting oil across the neck of the Venturi element, and a take-off hood communicating with the upper end of the partial combustion chamber through a restricted opening disposed eccentric to the neck opening of the Venturi element.

3. In an oil gas generator, means for generating combustible gases comprising, a main complete combustion chamber, a partial combustion chamber above the main chamber and communicating therewith through a restricted opening, a source of oil supply and an oil duct communicating with said source and opening into said restricted opening substantially radially thereof, means for supplying oil and air to the main chamber in proper proportions for maintaining substantially complete combustion therein, a take-off hood communicating with the partial combustion chamber, an air inlet valve mounted in the hood and yieldingly urged closed, and means actuated by the valve for controlling communication between said duct and the source of oil supply.

4. In an oil gas generator, means for generating combustible gases comprising, a main complete combustion chamber, a partial combustion chamber above the main chamber and communicating therewith through a restricted opening, means for supplying oil to said opening substantially radially thereof, a take-off hood communicating with the partial chamber and having an air inlet opening, an air inlet valve controlling the air inlet opening and yieldingly urged closed, and means actuated by said valve for controlling the supply of oil to said restricted opening.

5. In an oil gas generator, means for generating combustible gases comprising, a main complete combustion chamber, air admission tubes open to atmosphere at their upper ends and opening into the chamber adjacent the lower end thereof, means for supplying oil to the chamber, a partial combustion chamber above the main chamber and communicating therewith through a restricted opening, and means for supplying oil to said opening substantially radially thereof.

6. In an oil gas generator, means for generating combustible gases comprising, a casing, a main complete combustion chamber supported in the casing in spaced relation thereto, a partial combustion chamber seated on the main chamber and communicating therewith through a restricted opening, said partial combustion chamber having baffles spacing it away from the casing, tubes extending downwardly within the main chamber and open at their lower ends, certain of the tubes communicating at their upper ends with the atmosphere and the other tubes communicating at their upper ends with the

space between the casing and the partial combustion chamber, a plate closing the upper end of the space between the partial combustion chamber and the casing and having an opening in direct communication with the partial combustion chamber, the baffles being spaced below the plate, means for supplying water to the space between the casing and the main chamber, means for supplying oil to one of said tubes, means for supplying oil to said opening, and a take-off hood mounted on said plate over the opening therein.

7. In an oil gas generator, means for generating combustible gases comprising, a main complete combustion chamber, a partial combustion chamber, said chambers being disposed in juxtaposed relation and there being a restricted opening between the chambers and establishing direct communication therebetween, means for supplying oil and air to the main chamber in proper proportions for supporting combustion therein, means for projecting oil across said opening from the periphery thereof and in a sheet extending across the opening radially thereof, and means for causing the products from the main chamber to flow through said opening substantially axially thereof and through the sheet of oil substantially at right angles to the plane thereof and into the partial combustion chamber and for taking off the gases from said partial combustion chamber.

8. In an oil gas generator, means for generating combustible gases comprising, a main complete combustion chamber, a partial combustion chamber including a Venturi element having direct communication through its neck with the main chamber, said chambers being disposed in juxtaposed relation one above the other, means for supplying oil and air to the main chamber in proper proportions for supporting combustion therein, means for projecting oil substantially radially across the neck of the Venturi element and in a sheet extending across the neck radially thereof, and means for causing the products from the main chamber to flow through the venturi substantially axially thereof and through the sheet of oil substantially at right angles to the plane thereof and into the partial combustion chamber and for taking off the gases from said partial combustion chamber.

9. In an oil gas generator, means for generating combustible gases comprising, two chambers disposed in juxtaposed relation one above the other and communicating with each other through a restricted passage, means for supplying oil and air to one of the chambers in proper proportions for supporting combustion therein, means for projecting oil across the passage in a sheet extending across the passage substantially radially thereof, and means for causing the hot prod-

ucts of combustion to flow from said chamber through the passage substantially axially thereof and through the sheet of oil substantially at right angles to the plane thereof and into the other chamber and for taking off the resultant products.

In witness whereof, I hereunto subscribe my name this 11th day of November, 1926.
